(57) **CLAIM**

The ornamental design for an electronic balance, as shown and described.

DESCRIPTION

FIG. 1 is a perspective view of the top, front and left side of an electronic balance showing my new design;

FIG. 2 is another perspective view of the bottom, back and right side thereof;

FIG. 3 is a perspective view similar to FIG. 1 with a cover opened;

FIG. 4 is a front elevation view thereof;

FIG. 5 is a back elevation view thereof;

FIG. 6 is a left side view thereof;

FIG. 7 is a right side view thereof;

FIG. 8 is a top plan view thereof; and,

FIG. 9 is a bottom plan view thereof.

The broken lines in the drawing depict environmental subject matter only and form no part of the claimed design.
